HERSCHEL M. HEILIG, OF TECUMSEH, AND MERIMAN H. REED, OF BLUE SPRINGS, NEBRASKA, ASSIGNORS TO SAID HEILIG, AND HUGH SCILLEY, OF LEAVITT, NEBRASKA.

BEET-HARVESTER.

SPECIFICATION forming part of Letters Patent No. 757,190, dated April 12, 1904.

Application filed April 9, 1903. Serial No. 151,782. (No model.)

To all whom it may concern:

Be it known that we, HERSCHEL M. HEILIG, a resident of Tecumseh, in the county of Johnson, and MERIMAN H. REED, a resident of Blue Springs, in the county of Gage, State of Nebraska, citizens of the United States, have invented a new and Improved Beet-Harvester, of which the following is a full, clear, and exact description.

10 Our invention relates to improvements in beet-harvesters; and the objects that we have in view are, first, to provide means for digging embedded beets from the soil, and, second, to provide means which insure the loading of beets on a suitable elevator or conveyor and also tend to loosen the dirt adhering to the beets.

Further objects and advantages of the invention will appear in the course of the subjoined description, and the novelty will be defined by the annexed claim.

Reference is to be had to the accompanying drawings, forming a part of this specification, in which similar characters of reference indicate corresponding parts in all the figures.

Figure 1 is a side elevation of a portion of a beet-harvester equipped with a digging and elevator-loading mechanism of our invention. Fig. 2 is a plan view of the machine with our 30 improvements applied thereto, and Fig. 3 is a detail perspective view of a part of the present invention removed from the main frame of the beet-harvester.

In order that our improvements may be understood by those skilled in the art, we have 35 illustrated the same applied to a portion of an ordinary beet-harvester, wherein 5 designates the carrying-frame of the machine. This frame is provided at its rear portion with a 40 driving-axle 6, having ground-wheels 7. To the front portion of the machine-frame is attached a draft-tongue 8, and this front end of the machine is supported by caster-wheels 9, having adjustable connection with said machine-frame and controllable by a lever 10, one 45 end of which is within convenient reach of the driver occupying the seat 11, which is supported on the machine-frame. This frame 5 is also

equipped with a counter-shaft 12, which is driven by sprocket-gearing 13 from the driving-axes 6.

The machine-frame 5 is equipped with an adjustable frame 14, having pivotal connections with said machine-frame at 15, said adjustable frame being inclined rearwardly and downwardly from the machine-frame, and the rear portion of this adjustable frame is suspended by means of a hand-lever 16, which is mounted on the frame 5 and suitably connected with the free rear end of the pivoted frame 14. This adjustable frame is equipped with a pair of depending stocks 17, which are disposed in downwardly-converging relation. These stocks are fastened individually to the frame 14 in any suitable way, and they are 65 provided at their lower ends with the tapering shovels 18. These shovels are attached to or made in one piece with the stocks, and they project forwardly therefrom at a suitable angle. The shovels are tapered and curved in order 70 that they may readily pass through the soil when the machine is moved over the row of growing beet-plants, and these shovels occupy such spaced relation to each other as to pass through the furrow on opposite sides of the 75 beet-plants and in a way to engage therewith.

The stocks 17 are provided with rearwardly-extended arms 19, which are fastened individually to the stocks at points above the shovels 18. These arms are spaced relatively 80 to each other sufficiently to accommodate a beet-plant between them, and they serve to direct the plant which is dug from the soil by the operation of the shovels 18 upon an inclined elevator or carrier 20. The loading end of this carrier is supported in any suitable way at a point below and in rear of the guide-arms 19, so that the plants passing through these arms will be delivered directly upon the elevator. This elevator may be of 85 any suitable construction or pattern known to those skilled in the art, and it is mounted on the machine-frame 5 to assume an inclined position, substantially as indicated by Fig. 1. Any suitable means may be provided in the 90 machine for driving the elevator so that its 95

upper lead will travel adjacent to the arms 19 and in an upward and rearward direction, thus making provision for carrying the harvested beets away from the digging mechanism and 5 discharging said beets into any suitable apparatus, such as a dumping appliance or a loading-vehicle adapted to trail after the beet-harvester or alongside of the latter.

The stocks 17 are also equipped with rearwardly-extending arms 21, which are fastened to the stocks at points above the guide-arms 19. These arms prevent the beets when thrown rearwardly by the action of a spade mechanism from passing laterally beyond the 15 path of the elevator or carrier 20. The stocks are furthermore equipped with metallic shoes 22, which are fastened to the front edges thereof in a suitable way. These shoes serve to primarily take up the wear to which the 20 front ends of the stocks are exposed, and by fastening the shoes removably to the stocks they may be readily removed when worn and replaced by other shoes. The shoes shown by the drawings are preferably curved in 25 cross-section and fastened to the stocks at points between the shovels 18 and the guide-arms 19, said shoes being arranged to present their convex faces to the soil and to pass through the latter with minimum friction.

30 We will now proceed to describe the spading mechanism by which the beets are thrown or kicked rearwardly between the stocks and toward the conveyer or elevator, said spading mechanism serving also to remove the soil 35 which may adhere to the harvested beets. The frame 14 is equipped with a suitable number of shaft-bearings 23, in which are journaled the end portions of a crank-shaft 24, said shaft having a proper number of cranks 40 25, which are disposed radially to the shaft. As shown by Figs. 2 and 3, this shaft is provided with two cranks which extend in opposite directions from the bearing portions of said shaft, and these cranks are operably connected with spades or rakes 26. Each spade or rake consists of a suitable bar of metal or other material having a pointed extremity, although the detailed construction of the spade is not material, and each spade is loosely or 45 hingedly connected at a point intermediate of its length to one of the cranks 25 of the shaft 24. The upper end of each spade 26 has pivotal connection with a tension-rod 27, which extends forwardly from the crank-shaft and 50 the spade to the front end of the carrying-frame. Said rod 27 is fitted loosely in a suitable guide 28, provided at the front end of the frame 5, and this front portion of the rod passes loosely through a coiled tension-spring 55 29, one end of which is fastened to the frame 5 or the guide 28, while the rear end of the spring is made fast with one of the rods 27.

60 The crank-shaft 24 is adapted to be positively driven for the purpose of actuating the series of spades 26, and in the drawings we

have shown said shaft 24 as having a sprocket-wheel 30 fastened to one end thereof. This sprocket-wheel engages with a sprocket-chain 31, which is driven by a sprocket-wheel 32, made fast with the counter-shaft 12.

In the service of the machine it is drawn over a row of growing plants by a team of horses hitched to the tongue 8, and the lever 16 is properly adjusted to move the frame 14 to the required position. The shovels 18 are 75 drawn through the row of plants in a way to excavate or dig the beets from the row, and at the same time the shaft 24 is positively driven for the purpose of actuating the spades 26. As each spade moves in a downward direction 80 its point penetrates the ground, and when the crank 25 of the shaft moves rearwardly on the rotation of said shaft said crank operates the spade 26 to impel the latter forcibly in a rearward direction, the spade turning on the 85 loose connection between its upper portion and the rod 27. The spades 26 are thus actuated to throw the beets rearwardly between the stocks and toward the elevator, and the beets are thus delivered by the spading mechanism 90 and the digging devices upon said elevator 20, which serves to carry them in an upward and rearward direction to a suitable point of deposit.

The springs 29 are of such strength as to 95 hold the rods 27 in their normal positions to serve as the pivots for the spades 26; but when either spade encounters an obstruction, such as a rock or the like, the pull of the rod 27 increases the tension of the spring 28, so 100 that the spade will yield or give until it shall have passed the obstruction in its path.

Having thus described our invention, we claim as new and desire to secure by Letters Patent—

In a beet-harvester, the combination with a frame having guides, of pivotal rods slidably engaging with said guides on the frame, a crank-shaft, spading devices each connected to a crank of the shaft and to one of said pivotal rods, and springs connected to the frame and to the rods, each spring being of sufficient tension to hold the rod against slidable movement under normal conditions in the service of the spading device and adapted to give under undue strain when the spading device encounters an obstruction.

In testimony whereof we have signed our names to this specification in the presence of two subscribing witnesses.
